(57) **CLAIM**

The ornamental design for an aircraft suite, as shown and described.

DESCRIPTION

FIG. 1 is a right perspective view of the aircraft suite, with a tray feature thereof in a first position;

FIG. 2 is a left perspective view of the aircraft suite with the tray feature in the first position;

FIG. 3 is a plan view of the aircraft suite with the tray feature in a second position;

FIG. 4 is a right side elevation of the aircraft suite;

FIG. 5 is a front end elevation of the aircraft suite; and,

FIG. 6 is a rear end elevation of the aircraft suite.

In FIGS. 1 through 6, broken lines indicate environmental structure that forms no part of the claimed design.
